FIG. 1 is a face view of a stringed musical instrument, specifically a plucked Scytho-Ukrainian kobza, showing one form of my new design;

FIG. 2 is a fragmentary left side elevational view of the form shown in FIG. 1;

FIG. 3 is a fragmentary right side elevational view of the form shown in FIG. 1; and

FIG. 4 is a fragmentary face view of a stringed musical instrument, specifically a plucked Scytho-Ukrainian kobza, showing the fretted fingerboard of another form of my new design, the remainder of the instrument being the same as in FIG. 1 but omitted for convenience of illustration.

Portions of the drawing figures are shaded to indicate contrast in appearance. The strings have been omitted from FIGS. 2, 3 and 4 for convenience in illustration.
